US00D538950S

(12) **United States Design Patent** (10) **Patent No.:** **US D538,950 S**
(45) **Date of Patent:** **** Mar. 20, 2007**

(54) **LED LIGHT BULB**

(75) Inventor: **Fredric S. Maxik**, Weston, FL (US)

(73) Assignee: **Lighting Science Group Corporation**,
Dallas, TX (US)

(**) Term: **14 Years**

(21) Appl. No.: **29/254,208**

(22) Filed: **Feb. 17, 2006**

(51) **LOC (8) Cl. 26-04**

(52) **U.S. Cl. D26/2**

(58) **Field of Classification Search** D26/1-4;
313/313, 315, 317, 318, 493; 315/52, 53,
315/56, 57, 58

See application file for complete search history.

Primary Examiner—Marcus A. Jackson

(74) *Attorney, Agent, or Firm*—Haynes and Boone, LLP

(57) **CLAIM**

The ornamental design for an LED light bulb, as shown and described.

DESCRIPTION

FIG. 1 is a bottom perspective view of an LED light bulb showing my design;

FIG. 2 is a top perspective view thereof;

FIG. 3 is a front elevational view thereof, the rear being a mirror image of the front;

FIG. 4 is a left side elevational view thereof, the right side being a mirror image of the left side;

FIG. 5 is a top plan view thereof; and,

FIG. 6 is a bottom plan view thereof.
